DESIGN FOR A BRASSIÈRE

Sara Stein, Brooklyn, N. Y.

Application February 25, 1938, Serial No. 75,414

Term of patent 14 years

To all whom it may concern:

Be it known that I, Sara Stein, a citizen of the United States and resident of New York city (Borough of Brooklyn), in the county of Kings and State of New York, have invented a new, original, and ornamental Design for a Brassière, of which the following is a specification, reference being had to the accompanying drawing, forming a part thereof, and of which Figure 1 is a view in front elevation of a brassière showing my design; Fig. 2 is a perspective view of the brassière shown in Fig. 1; and Fig. 3 is a view in rear elevation thereof.

I claim:

The ornamental design for a brassière substantially as shown.

SARA STEIN.
